UNITED STATES PATENT OFFICE

2,279,132

DOBBY CORD TERMINAL

Breckinridge T. Clark, Danielson, Conn., assignor to E. H. Jacobs Mfg. Co., Inc., Danielson, Conn., a corporation of Connecticut

Original application June 22, 1939, Serial No. 280,509, now Patent No. 2,240,982, dated May 6, 1941. Divided and this application March 6, 1941, Serial No. 382,092

1 Claim. (Cl. 24—123)

My present invention is a divisional of my prior application 280,509, filed June 22, 1939, now Patent No. 2,240,982, dated May 6, 1941, on one form of my Die-cast dobby cord terminal invention.

The advantages of die-casting a terminal at each end of a dobby cord are now well recognized, and the important features of my said pending improved constructions and methods consist in the utilization of a hardened steel, wear-resisting eyelet, U-shaped, or hook member united and bonded with both the wire core, or heart, and with a braided sheath or covering.

My present invention aims to improve and perfect this feature and to provide a terminal structure particularly suited for the die-casting operation, although it can be likewise formed by a hot metal molding or welding operation.

In the present construction I provide the wear-resistant hardened steel or loop member with a pair of extending shanks or arms adapted to lay in close contact with the projecting end of the reinforcing wire core of a dobby cord, such as is shown in said prior Patent 2,152,397, and thereupon to firmly bond the extending arms and wire together by flowing a mass of molten metal therearound, preferably by the quick and simple die-cast method.

A further and important feature consists in an arrangement whereby my present improvement has cooperating means to bind the two arms of the eyelet member with the core, as well as to interlock the same and the molten metal used for the bonding action.

In carrying out this latter feature, I prefer to pre-form the extending shank or arm members with grooves or other irregularities which will permit both the core and interlocked shank or arms and the molten metal to flow therein and thus firmly to bind same with the metal as in die-casting, welding, molding, or the like, as well also as to more firmly bind the arms of the eyelet member to and about the reinforcing wire core.

A further important feature consists in the snugness and compactness with which my dobby cord terminal can be embodied, by having the plurality of arms of the eyelet member straddling and telescoping with the projecting wire of the reinforcing core, and thus also save the quantity of die-cast metal employed.

While I may, if desired, utilize one extending arm or portion from the eyelet and interlock same with the reinforcing wire core, I prefer to utilize two or more extending arms from the eyelet member which straddle and interlock with the wire of the cord.

Referring to the drawing illustrating preferred embodiments of my present invention:

Fig. 1 illustrates a modified form wherein the wire end is interlocked with the shank of the eyelet member;

Fig. 2 illustrates the same in cross-section with the die-cast molten metal completing the union, and

Fig. 3 is a view of the completed terminal.

As shown in the drawing, a dobby cord section comprising a braided sheath 1 and a wire core 2 of the usual type is prepared by removing a portion of the sheath 1 from the end to expose the projecting wire core 2. An attaching hard metal hook or eyelet member 15 has threads, corrugations, roughened surfaces, or the like around which the wire core 2 of the dobby cord 1 may be wound in firm contact therewith, as indicated at 18, thus giving a firm metal-to-metal connection between the eyelet member 15 and the core 2. The molten metal is then applied by die-casing, as shown at 10, firmly enclosing, uniting, binding, and interlocking the metal about the wrapped core 2 and shank 16 of the eyelet member, and, furthermore, forming simultaneously a ferrule 12.

Thus a compact, strong, firm, rigid, interlocking construction is obtained, firmly binding the wear-resisting member 15 directly to the wire core 2 and to the enclosing sheath 1. This terminal is applied to each end of the dobby cord, as will be readily understood.

As clearly shown in Figs. 1, 2, and 3, a strong positive interlocking structure is illustrated, wherein the wear-resisting or hardened steel-engaging member is positively interlocked with the wire core. Thus, I have shown a hook 15 having a screw-threaded shank 16 around which the projecting end portion 18 of a wire core is wrapped, as clearly shown in Figs. 2 and 3.

The hook 15 can, of course, be an eyelet, if desired, and the hook can be closed against the shank to make a loop, if desired.

With this construction, the molten metal 10 is then applied by molding, welding, or die-casting as above explained, and the terminal completed, providing a very strong interlocking construction between the wire of the core 2 and the member 15.

It will be noted that I have obtained a strong, compact, firm interlocking construction with the hook, eyelet or U-shaped member of wear-resisting material, preferably hardened steel, and with the same having a shank, or shanks, in direct contact with the wire core of the dobby cord 6 exposed for an appropriate length for such interlocking and the completion of the union between the eye-

let, hook, or U-shaped member and the dobby cord being effected by simultaneously uniting the same with molten metal 10 and forming a ferrule 12, thus providing a complete finished terminal.

I claim:

A reinforced dobby cord of the kind described, comprising a braided textile sheath and a wire core, a metallic fastening member having an eye-let, hook, or the like, and a shank formed with a

plurality of grooves, the reinforcing wire projecting from the end of the sheath and interlocking with the said shank by engaging the grooves of the shank of the metallic fastener, and molten metal covering, protecting, and bonding the interlocked portion of the shank and wire, and forming a ferrule on the end portion of the sheath.
